UNITED STATES PATENT OFFICE

CLARENCE C. SHIPP, OF INDIANAPOLIS, INDIANA

RADIATOR-BOX BASE END CLOSURE

Application filed October 21, 1929. Serial No. 401,126.

This invention relates to housing boxes for steam or hot water radiators and deals particularly with means for obtaining a tight fit of the box base about interconnecting nipples of the radiator coils or sections.

The radiator boxes referred to herein are housings about radiator sections through which air may be drawn and passed across the sections for the purpose of heating and ventilating a room. The box base is that part of the housing which encloses the lower ends of the sections. Heretofore considerable difficulty has been encountered in providing a suitable closure of the box base around the section-connecting nipples so as to provide a tight closure so as to prevent air from leaking out onto the floor of the room.

It is the primary object of this invention to provide a simple and efficient means for readily closing a gap in the end of the box base that will also serve as means for retaining the upper housing in alignment across its junction with its box base. Another object also is to provide such means as may be inserted after the radiator and box base are assembled one with the other. Another object resides in the economy effected by the employment of the invention in the saving of material as well as of labor in installation.

These and other objects will become apparent in the following description of the invention as illustrated in the accompanying drawing, in which—

Fig. 1, is a view in end perspective of a radiator housing and box base to which my invention is applied;

Fig. 2, a vertical section on the line 2—2 in Fig. 1;

Fig. 3, is a horizontal section on the line 3—3 in Fig. 1;

Fig. 4, a modified form of the closure plate; and

Fig. 5, a vertical section on the line 5—5 in Fig. 4.

Like characters of reference indicate like parts throughout the several views in the drawing.

Referring first to Fig. 1, a box base 10 is

fitted around the lower ends of the central sections 11 of a radiator with a U-shaped opening 12 cut through each end from the upper edge to permit the passage thereacross of the connecting nipples 13 between the inner section 11 and the outer section 14.

Supported by the base 10 is the housing 15 made in two sections having ends 16 and 17 bent around to pass between the radiator sections, all in the usual and well known manner. Such construction, however, leaves a gap above the nipple 13 and the lower ends 16 and 17 through the end of the base 10 through which air may pass. The piece 18 cut from the top of the U-shaped hole 12 is utilized and secured to a plate 19 which has its upper end, Fig. 2, bent around and downwardly over the piece 18 for a distance and thence around and upwardly to form a channel 20 into which the lower edges of the ends 16 and 17 may be entered and yieldingly retained when the plate 19 is slipped downwardly on the inside of the end of the base 10 with the piece 18 serving as a guide against the vertical edges of the upper portion of the hole 12. Since the piece 18 is of the same thickness as that of the end 10, the back side of the channel 20 will contact the outer face of the box base end and grip it therealong. The channel 20 in addition to serving as a means of retaining the ends 16 and 17 in alignment also additionally serves as a means for retaining the plate 19 in contact against the inner face of the box base end as well as retaining the piece 18 carried thereon within the upper gap of the hole 12 thereby forming a close snug fit completely closing the gap left in the box base end above the nipple 13. By reason of the piece 18 being carried as above indicated, the plate 19 is prevented from being moved horizontally.

Referring to Figs. 4 and 5 the piece 18 is here shown as being omitted with plate 19 and channel 20 only employed.

While such a plate 19 may be effectively used to close the opening through the end of the base 10 above the nipple 13, it is not so desirable for the reason that there is the offset presented across the hole by reason of the plate 19 being spaced back from the sur-

face of the box end by the thickness of the box base metal.

It is thus to be seen in the foregoing description that the heretofore troublesome problem of effecting a closure about the radiator section connecting nipple is solved and that a very neat structure is effected that performs the combined function of closing the gap above the nipple as well as receiving, operating, and aligning the ends of the radiator housing all accomplished by simply inserting the plate 19 into position without the need of tools or additional parts.

I claim:

1. In a radiator box, a base having a radiator section nipple opening cut through one end from the upper edge, a plate adapted to contact the face of the base end having its lower end cut to fit snugly over a nipple extending through said opening, and a channel integrally formed along the top edge of the plate to hook over the top edge of said base and present an opening into the channel along the top side, and a piece carried by said plate having guiding edges adapted to contact the sides of said opening.

2. In a radiator box, a box base having a U-shaped opening cut down from the top edge in an end of the base, a housing having an adjoining end extending across the end of said base, a plate having an upper hook engaging over the top edge of the base to carry said plate across said opening, and a channel extending from the plate and receiving the under edges of said housing ends therein, the under side of said plate being cut away in a semi-circle whereby a substantially circular hole is formed in the base end, the upper boundary of which is the under edge of the plate and the lower boundary of which is the lower end of said opening.

3. In a radiator box, a box base having a U-shaped opening cut down from the top edge in an end of the base, a housing having adjoining ends extending across the end of said base, a plate having an upper hook engaging over the top edge of the base to carry said plate across said opening, and channel extending from the plate and receiving the under edges of said housing ends therein, the under side of said plate being cut away whereby a substantially circular hole is formed in the base end, the upper boundary of which is the under edge of the plate and the lower boundary of which is the lower end of said opening, and a piece carried by said plate filling in said opening above said hole.

4. A new article of manufacture comprising a plate having a semi-circular shaped lower edge and a channel across its top formed by bending the top end around downwardly, then upwardly and back downwardly and finally upwardly, the channel end being longer than the lower end.

5. A new article of manufacture comprising a plate having a semi-circular shaped lower edge and a channel across its top formed by bending the top end around downwardly, then upwardly and back downwardly and finally upwardly, and a secondary plate fixed on the said first plate having its upper end carried between said channel and the first plate and its lower edge cut to coincide with the curvature of the first plate.

6. A radiator box base closure comprising a horizontally disposed channel member and a depending member having its under side curved substantially semi-circular, the upper end of said depending member being engaged by said channel member, and the lateral edges of the depending member being substantially tangential to the curve of its under side, and a plate extending from each lateral edge of the depending member spaced parallel to but rearwardly from its front face.

7. A radiator box base opening closure comprising a horizontal member adapted to engage over the edge of the box, and a plate depending from said member, and a piece in a parallel plane with the plate to fit in said opening.

In testimony whereof I affix my signature.

CLARENCE C. SHIPP.
